UNITED STATES PATENT OFFICE

2,327,335

PRESSURE PROPORTIONER

Lewis W. Boerner, Newton Square, and Francis J. Hogenmiller, Ardmore, Pa., assignors to National Foam System, Inc., Philadelphia, Pa., a corporation of Delaware

Application April 16, 1942, Serial No. 439,210

4 Claims. (Cl. 299—84)

This invention relates generally to apparatus for use in the generation of mechanical or air foam employed in the extinguishment of fires and more particularly to an improved construction of apparatus for introducing a foam stabilizing solution into a stream of water.

In the production of the so-called mechanical or air foam, the usual procedure involves flowing a high velocity stream of water laden with a foam-forming substance through a conduit to a point therein where the stream is finely subdivided or dispersed and where a suitable gas (usually air from atmosphere) is entrained in such manner as to cause a mingling of the liquid and gas as they move in the conduit toward the point of discharge therefrom. Typical of this method of producing mechanical foam is that which is described in United States Letters Patent No. 2,106,043, granted January 18, 1938, and No. 2,198,585, granted April 23, 1940.

In order to insure the production of foam of the desired uniform quality, it is necessary that the rate of introduction of the foam-forming material into the flowing stream of water be proportional to the rate of flow of the water, while in order to insure an adequate projection of the foam from the discharge nozzle it is necessary to maintain a considerable head of pressure upon the water stream. It is among the principal objects of this invention to provide an apparatus by which both of these desired objectives may be secured.

More specifically, an object of the present invention is the provision of an apparatus which not only insures maintenance of a maximum head of pressure in the water stream to provide for adequate projection of the stabilized foam, but which also utilizes the full available head of pressure to inject the stabilizing material into the water stream at a rate which is automatically proportioned to the rate of flow of the water stream.

A further object of the present invention is to provide an apparatus of the character aforesaid which includes means for utilizing the full head pressure of the water stream to force the foam-forming material from its source of supply into the water stream without, however, effecting any substantial mixing of the water with the supply of foam-forming material.

A still further object is to provide an apparatus of the character aforesaid with a container for the foam-forming material which is so operatively associated with the water conduit as to insure the continuous introduction of such

material into the flowing water stream until the supply is exhausted, the container being adapted for ready removal and replacement by another filled container should a further supply of foam stabilizer be required. In addition, the container itself is so constructed and designed as to facilitate its being readily and quickly filled with foam stabilizer without incurring foaming of the latter per se.

Still other objects and advantages of the present invention, such as the provision of a unit which is exceedingly compact and simple in construction, which is readily portable and easily operable without requiring the constant attendance of an operator and which is extremely efficient in use, will appear more fully hereinafter, it being understood that the invention consists substantially in the combination, construction, location and relative arrangement of parts, all 10 as will be described in detail hereinafter, as shown in the accompanying drawings and as finally pointed out in the appended claims.

In the said accompanying drawings, which illustrate a preferred embodiment of the present 15 invention:

Figure 1 is a side elevational view, shown partly in vertical section, of an apparatus constructed in accordance with and embodying the principles of the present invention;

Figure 2 is a top plan view of the proportioner 20 unit with the cap removed;

Figure 3 is a vertical sectional view of the unit removed from the stabilizer container;

Figure 4 is a horizontal sectional view taken 25 along the line 4—4 of Figure 3; and

Figure 5 is an end elevational view of the outlet end of the proportioner unit.

Referring now to the drawings and more particularly to Figure 1 thereof, it will be observed 30 that the apparatus of the present invention generally consists of a refillable container 10 within which is stored a supply of foam stabilizing solution and an injecting device 11 which is operatively associated with the container 10 for delivering the foam solution from the container into a flowing stream of water at a rate which varies proportionally to the rate of flow of the water. The foam solution injecting unit is shown more particularly in Figures 2 to 5, inclusive, and is adapted to be detachably connected to the container 10 by the simple expedient of screwing the lower end part 12 into an interiorly threaded fitting 13 with which the container 10 is equipped.

The injecting unit 11, as most clearly appears 35 in Figure 3, essentially consists of a one-piece

body member, the interior of which is longitudinally bored to provide a Venturi tube 14 through which a stream of water from a suitable source of high pressure supply is adapted to be projected in the direction indicated by the arrows. The water inlet end of the unit is interiorly threaded as at 15 for connection, by means of a suitable coupling and hose 16 (see Figure 1) to a hydrant or other source of water under suitable pressure. The outlet or discharge end of the unit is exteriorly threaded as at 17 for connection, by means of a suitable coupling 18, to a hose 19 through which the water mixed with the foam stabilizer solution is delivered to the point where air is entrained therein and thence discharged in the form of fire extinguishing foam. The manner of and means for effecting the entrainment of air or other gas into the stream of water laden with the foam forming substance forms no part of the present invention and, therefore, no detailed description thereof will be given herein, the present invention being limited more particularly to the means for introducing into the water stream the requisite quantity of the foam stabilizing solution. It will be understood in this connection that this invention is not limited to the use of any particular type of foam forming material. Usually this material is in the form of an aqueous solution of a secondary extract of licorice, of saponin or of other suitable substance having the capacity of being foamed when a gas is injected into a solution or suspension thereof.

In addition to the Venturi passage extending longitudinally through the injecting unit 11, the latter is provided with a vertically extending bore or passage 20 of substantial dimension. The upper end of this vertical passage is surrounded by an exteriorly threaded neck 21, which is adapted to be closed by a cap 22 suitably threaded thereon and having a pair of oppositely projecting arms 22a—22a for facilitating screwing of the cap tightly into position. The lower end of the vertical passage 20 is surrounded by the exteriorly threaded sleeve-like projection 12 which is adapted to be threaded into the fitting 13 of the container. The passage 20, which extends substantially at right angles to and is in free communication with the Venturi tube passage, may be termed the filling opening. In addition to the Venturi passage and the said filling opening, the unit 11 is provided with an auxiliary passage 23 of reduced diameter which connects the low pressure portion of the Venturi tube at the point 24 with a vertical bore 25 extending upwardly into a boss 26 which projects interiorly of the central portion of the wall of the filling opening. This auxiliary passage 23 is formed of the intercommunicating angularly related portions as shown in Figure 3, the outer extremities of which are tapped, as at 23a—23a, for reception of suitable closure plugs. The angularly related portions of the passage 23 are formed by drilling intersecting holes in the part 24a of the main body member, it being apparent that such construction facilitates locating as desired the position of the point 24 with reference to the low pressure section of the Venturi passage.

Securely fitted into the sleeve-like lower end 12 of the injecting unit is a tube 27, the length of which is determined by the size of the container 10. Generally, this tube 27 is of such length that when the unit 11 is operatively connected with the tank 10, the tube extends downwardly into the tank for approximately three-fourths of the depth of the latter. Provided in

5 the upper extremity of the tube 27 immediately below the lower extremity of the sleeve are a plurality of circumferentially spaced openings 28. The function of this tube 27 and of the said openings 28 therein will presently appear.

As appears most clearly in Figures 3 and 4, the vertical bore 25 formed in the internal boss 26 is disposed interiorly of the circumferential line of the tube 27, this bore 25 being in turn securely 10 fitted with a tube 29 which normally extends downwardly into the container to a point just short of the bottom thereof. Due to the location of the supporting boss 26 relatively to the sleeve 12 the tube 29 fitted into and supported by said 15 boss is arranged interiorly of the tube 27, which is fitted into and supported by the sleeve 12. The upper end of the tube 29 is provided with an opening 30 which is in communication with the passage 23 previously referred to, and thus, the 20 lower end of the tube 29 freely communicates with the Venturi passage at the point 24 in the low pressure portion thereof.

It will be understood that in the operation of the apparatus of the present invention, the container 10 for the foam stabilizing solution is connected to the injecting unit 11, as shown in Figure 1, the container 10 being normally filled with the foam solution to such level as to just about 25 freely expose the openings 28 in the filling tube 27. In this condition of the apparatus, the cap 22 will be tightly secured in place to close the upper end of the filling opening. Water under pressure from a suitable source of supply is then 30 delivered by the conduit 16 to the inlet end 15 of the injecting unit 11 and passes through the Venturi passage 14 thereof in the direction of the arrows of Figure 3. As the water enters the unit 11, a portion of it flows under considerable pressure downwardly through the filling opening and 35 discharges through the openings 28 in the filling tube 27 to fill the free space in the top of the container 10 above the level of the foam solution contained therein. The water which so enters the container through the openings 28 exerts 40 a considerable pressure on the solution in the container 10. Due to the fact that the lower end of the tube 29 is in free communication with the low pressure portion of the Venturi passage at the point 24, there exists a pressure differential 45 between the latter point and the point of application of the water under pressure upon the upper surface of the foam solution, which results in a flow of the foam solution upwardly through the tube 29 and through the passage 23 into the 50 stream of water flowing through the low pressure portion of the Venturi passage 14. This flow of foam solution from the container 10 into the stream of water flowing through the Venturi passage of the injecting unit will continue, of course, so long as a stream of water under suitable 55 pressure is flowed through the unit and until the supply of foam solution in the container 10 is completely exhausted. Inasmuch as the flow of the foam solution upwardly through the tube 29 is dependent upon the pressure differential existing between the high and low pressure portions of the Venturi passage, it will be apparent that by proper design of the cross-sectional areas of said high and low pressure portions of the 60 Venturi passage and the proper location of the point 24 in relation to the point of application of the high pressure to the upper surface of the foam solution in the container 10, the ratio of the rate of flow of the foam solution to the rate 65 of flow of the water stream through the Venturi 70 75

passage may be predeterminedly established and maintained.

As the water under pressure from the source of supply enters the container 10 through the passages 28 of the filling tube, it is laterally distributed uniformly over and exerts an even pressure upon the entire upper surface of the foam solution, there being little, if any, mingling of the water and foam solution in the container 10. The openings 28 and the passage 20 leading thereto are of such substantial size that substantially the full head of water pressure is exerted upon the foam stabilizer solution contained in the container 10. As the foam solution is withdrawn from the container for injection into the water stream at the point 24, additional water enters the container so as to maintain a constant pressure head upon the foam solution until the supply of the latter is completely exhausted, at which time the container 10 will be filled, of course, entirely with water. In such event, the water supply may be cut off and the container 10 drained of its water preliminarily to its being refilled with a further supply of foam solution. Or, if desired, the container 10 when so filled with water may be entirely removed and replaced by a second container filled with the foam solution. To facilitate rapid emptying of the water from the container 10 when the latter is not disconnected from the injecting unit 11, any suitable type of quick-acting valve (not shown) may be provided at the bottom of the container, this valve being normally opened for discharge only upon interruption of the water supply and removal of the upper closure cap 22.

In order to refill the container 10 with foam solution after it has been cleared of its accumulated water, it is merely necessary to close the bottom valve of the container and then fill it by way of the filling opening 20 and the filling tube 27. Inasmuch as the latter projects downwardly into the container for some considerable length, the filling of the container is accomplished with a minimum of agitation of the foam solution and consequently foaming of the latter in the container 10 during the filling operation is substantially inhibited, if not altogether avoided.

It will be understood, of course, that the invention is capable to various changes and modifications which may be made from time to time without departing from the real spirit or general principles thereof, and it is accordingly intended to claim the invention broadly, as well as specifically, as indicated in the appended claims.

What is claimed as new and useful is:

1. In an apparatus for injecting a solution of foam forming material into a flowing stream of water, a device adapted to be interposed in a conduit for delivering the water under pressure from a source of supply to a point of discharge, said device being characterized in that it is provided with a Venturi passage extending longitudinally therethrough and with a pair of passages extending laterally of and in free communication respectively with the high and low pressure sections of said Venturi passage, the lateral passage in communication with the high pressure section being of substantially greater cross-sectional area than the lateral passage in

communication with the low pressure section, a pair of tubes respectively fitted into said lateral passages, and a closed container for the foam forming material secured to the device aforesaid in embracing relation with respect to the said tubes, the lower ends of both tubes being open and the tube in communication with the high pressure section of the Venturi passage having means for permitting the delivery of water from said high pressure section directly upon the upper surface of the solution in said container whereby said solution is forced upwardly through the other tube into the low pressure section of the Venturi passage.

2. In an apparatus for injecting a solution of foam forming material into a flowing stream of water, and which device is adapted to be interposed in a conduit for delivering the water under pressure from a source of supply to a point of discharge, an injecting unit characterized by the provision of a Venturi passage extending longitudinally therethrough and with a pair of auxiliary passages extending laterally of and in free communication respectively with the high and low pressure sections of the Venturi passage, the lateral passage in communication with the low pressure section of the Venturi passage being extended to a point interiorly of the lateral passage in communication with the high pressure section of the Venturi passage, a pair of tubes respectively fitted into the terminal extremities of said lateral passages with the low pressure tube disposed interiorly of the high pressure tube, and a normally closed container for the foam forming solution secured to the injecting unit with the tubes aforesaid projecting interiorly thereof, the low pressure tube having its lower end open and terminating just short of the bottom of the container, while the high pressure tube is provided in the portion thereof immediately below the top of the container with a plurality of openings through which water from the high pressure side of the Venturi tube may be delivered upon the upper surface of the solution in the container.

3. In an apparatus of the character defined in claim 2 wherein the lateral passage which is in communication with the high pressure section of the Venturi tube extends freely to either side of the Venturi tube axis, one end of said lateral passage being in the form of an annular flange threaded to receive a closure cap, while the opposite end of said passage is also in the form of an annular flange to which is adapted to be threadedly secured the container for the foam forming solution.

4. In an apparatus of the character defined in claim 2 wherein said passage which is in communication with the high pressure section of the Venturi tube is extended to one side of the injecting unit to provide an opening through which the foam forming solution may be poured to fill the container and wherein the tube which is connected to said passage in continuation thereof is of substantial length and is open at its bottom end.
